Application September 27, 1954, Serial No. 458,442

3 Claims. (Cl. 86—1)

This invention relates to electric blasting caps and more particularly to explosive devices housed in thermoplastic shells.

Explosive devices such as plastic blasting caps have been proposed heretofore; but considerable difficulty has been encountered in obtaining a waterproof seal between the blasting cap case or shell and the bridge plug.

It is therefore an object of this invention to provide a waterproof plastic detonator overcoming the disadvantages of previous thermoplastic detonators. Another object of this invention is to provide a novel thermoplastic detonator. A more specific object of this invention is to provide a novel solvent-less method of sealing thermoplastic detonators. A further object is to provide a method of sealing detonator components formed of difficultly soluble thermoplastic materials. A still further object is to heat seal a thermoplastic explosive device in a safe and efficient manner.

The manner in which these and other objects are accomplished in accordance with this invention will be fully understood when the following description thereof is read in connection with the drawing, in which:

Figure 1 is a plan view of a thermoplastic detonator in position to be sealed in accordance with one embodiment of this invention.

Figure 2 is a cross-sectional view illustrating a detonator sealed in accordance with an embodiment of this invention.

Figure 3 is a plan view of one type of heat-sealing tool that may be used in carrying out the process of this invention, and

Figure 4 is a cross sectional view taken near the tip of the tool shown in Figure 1.

In accordance with this invention, the foregoing objects are accomplished, generally speaking, by applying heat to the thermoplastic material at the juncture between the thermoplastic case housing the charge of explosive and the thermoplastic closure for the case so as to cause interflow of the plastic materials adjacent the juncture. In other words, this invention contemplates a method of sealing explosive devices such as plastic electric blasting caps in which the external juncture of the bridge plug and case is heated at least to the melting points of the thermoplastic materials composing the bridge plug and case, and pressure is applied in the vicinity of the juncture in such a manner as to induce the plastic materials making up the component parts to flow together, thus forming a waterproof seal. More specifically, the objects of this invention may be attained by forming two substantially parallel and adjacent furrows, one on either side of the external juncture, by means of a heated member, whereby the material displaced by the formation of the furrows intermixes and forms a ridge over the external line of contact between the bridge plug and shell wall. As a result of this process, the external line of contact between the bridge plug and the detonator case is covered by a beading formed by a combination of the materials displaced from the plug and case.

Alternatively, a single furrow can be formed along the line of juncture of the plug and the case, equal quantities of thermoplastic material being displaced from each member, and then filled with the displaced thermoplastic material while still in a molten condition, so as to form a uniform seal over the original juncture. When this variation of the invention is utilized, the surface over the original juncture is smooth and unbroken, and the original configuration of the explosive device is maintained.

10 The temperature to which the materials are heated in accordance with the process of this invention is not critical, but in general it must be in a range above the melting points of the plastic materials being treated and usually must be below their decomposition points. Temperatures 15 above the decomposition points may be tolerated, however, in instances when the duration of the heating is sufficiently brief to prevent significant deterioration of the plastic material.

19 The seal between the bridge plug and the case is formed 20 by the application of a grooved heated member to the detonator, the groove spanning the external joint between the bridge plug and the case. The grooved tool may be rotated about the detonator, or if desired the tool may be maintained stationary while the detonator in contact 25 with it is rotated so that the seam between the bridge plug and the detonator case is effectively welded, in either event contact between the heated tool and the full length of the juncture line being achieved by relative rotation of the heated member and the detonator. Alternatively, the 30 heating member may be of a type that completely encircles and embraces the detonator at the point of juncture between the bridge plug and detonator housing, and when such a tool is utilized relative rotary motion between the detonator and the tool is not essential to the formation 35 of a waterproof seal.

While it is preferable to heat and groove the detonator in the same operation, this invention also encompasses processes in which that portion of the detonator being treated is heated as by the application of a heating tool, 40 and while thus heated and in a readily deformable state is brought into contact with an unheated forming tool to complete the operation.

The process of this invention is particularly well adapted to provide an efficient means for sealing electric detonators having a thermoplastic case which is closed by means 45 of a two-diameter or shouldered thermoplastic bridge plug as shown, for example, in U. S. 2,382,921, issued August 14, 1945, to Seavey. When the invention is utilized in sealing this type of detonator, the sealing operation is, of course, executed on the lateral surface of 50 the detonator. It should be understood however that this process is equally applicable to the sealing of electric detonators in which the top surface of the bridge plug is flush with the top edge of the detonator case. When 55 used in connection with this type of cap, the heating member is of course contacted with the annular juncture between the plug and the case, and the plug is maintained in position by means of internal stops or by the internal taper of the shell wall.

60 The term "thermoplastic" as used herein denotes resinous materials that are rendered soft, moldable and capable of fusion by the action of heat. Any thermoplastic suitable for the formation of the case may be used, examples being synthetic resins such as, for instance, cellulose esters, cellulose ethers, polyvinyl chloride, polyvinyl acetate, polyethylene, acrylic and methacrylic polymers, polystyrene, and polystyrene co-polymers, polyamides, ethyl cellulose, chlorinated rubber, and modified isomerized rubber, as well as natural resins such as, 65 for instance, copols, accroids, and protein plastics and combinations thereof, including where desirable suitable plasticizers.

The terms "electric blasting cap" and "electric detonator" as used herein are meant to include all types of electrically operated explosive initiators such as instantaneous caps, delay caps, squibs, fuses, and the like; and the term "explosive device" is used to denote all types of explosive initiators contained in a plastic housing.

The various features of the invention will become more apparent and will be readily understood by those skilled in the art when the illustrative embodiment of the invention is read, in connection with the attached drawing.

As shown in Figure 1, a detonator loaded with an appropriate explosive train enclosed in a polyvinyl chloride case 1, the mouth of which is closed by a bridge plug 2 of the same composition, is secured in a chuck 4 capable of being rotated. The bridge plug is provided with a pair of lead wires which may be joined together after emergence from the plug as shown at 3. The detonator is then rotated axially at about 80 revolutions per minute and tool 5 which is maintained at a temperature of about 145° C. is brought into contact with the rotating detonator, in such a manner that groove 6 in the face thereof spans the line of juncture between the detonator case 1 and the bridge plug 2, and the axis of the groove is parallel to this line of juncture. After the tool has been brought into contact with the detonator, it is moved in slightly to make the plastic material flow toward the middle of the groove, where it is ironed smooth. In the present example, wherein the external diameter of the detonator case is about 0.275 inch and the shell wall is about .037 inch thick, it was found that best results were obtained when the heating tool was moved about $\frac{1}{64}$ inch toward the center of the detonator after contact was made with its periphery while the tool was moved about $\frac{5}{16}$ inch tangentially.

It will be understood, of course, that the amount of deformation will not necessarily be the same in all instances, but that it will vary with the size of the detonator and the characteristics of the materials being joined together. The deforming contact must be maintained until the materials forming the bridge plug and the shell are substantially intermixed to form a uniform beading covering the original gap between the bridge plug and the detonator housing, thus providing an effective seal. In the present case, this result was obtained by maintaining such contact for about 8 seconds using a single tool to deform, mix and form the seal ring.

As shown in the sealed detonator of Figure 2, the bridge plug and case are fused together at their point of contact and the original boundary line 7 has been eliminated throughout a substantial portion of the wall thickness, being replaced by beading 8 which is a welded mixture of the bridge plug and shell components. While heat sealing of a detonator charged with explosive would ordinarily be considered a hazardous undertaking by those skilled in the art, it will be seen that such heat sealing is accomplished in accordance with this invention by a safe and efficient method lending itself to mass production.

For purposes of illustration in the present example, the detonator lead wires were severed a few inches from the bridge plug; but in practice, lead wires of normal length can be rotated along with the detonator by conventional means not forming a part of the present invention.

Although the above specific embodiment is concerned with an electric blasting cap in which the bridge plug and detonator case are both formed of the same material, viz., polyvinyl chloride, it will be readily appreciated that the bridge plug and case can be formed of dissimilar materials, provided they are joinable by fusion.

Figure 3 illustrates another type of heat-sealing instru-

ment that may be employed to obtain the benefits of this invention. This tool consists essentially of two hinged members 7 having cooperating semi-circular depressions 8 adapted to embrace and encircle an electric detonator 5 when members 7 are brought into contact with one another. When this tool is used it is heated by appropriate means to a point above the melting points of the thermoplastic materials of which the bridge plug and detonator case are composed. After a plastic detonator has been 10 positioned within the semi-circular depressions 7 in such a manner that the line of juncture between the bridge plug and the detonator casing is intermediate the parallel forming lands 9, members 7 are brought together. The bridge plug and casing are thus heated and indented and 15 the material displaced merges together to form a continuous, non-porous weld between the plastic components of the detonator.

From the foregoing description, it is apparent that many modifications of the process hereinbefore described 20 will present themselves to those skilled in the art without departing from the spirit and scope of the invention as set forth in the appended claims.

Having thus described the invention, what is claimed is:

1. In the manufacture of electric blasting caps, the 25 process comprising heating an assembled electric blasting cap having a thermoplastic bridge plug and a thermoplastic case to a temperature above the melting points of said thermoplastic materials in the area of the external line of juncture of the bridge plug and case, forming a 30 furrow in the heated portion of the external surface of the bridge plug and another furrow in the heated portion of the external surface of the case, said furrows being parallel to and co-extensive with the external juncture of the bridge plug and case, and intermixing the molten 35 materials displaced by said furrows over the external juncture of the bridge plug and the case.

2. In the manufacture of electric blasting caps, the 40 process comprising heating an assembled electric blasting cap having a thermoplastic bridge plug and a thermoplastic case to a temperature above the melting points of 45 said thermoplastic materials in the area of the external line of juncture of the bridge plug and case, and subjecting the heated area to a deforming pressure whereby a beading spanning the said external line of juncture is formed, said beading consisting of an intermixture of the thermoplastic materials from the bridge plug and casing.

3. In the manufacture of electric blasting caps, the 45 process comprising providing an assembled electric blasting cap having a thermoplastic bridge plug and a thermoplastic case, contacting said electric blasting cap along 50 the line of external juncture of the bridge plug and case with a forming tool having a groove in the face thereof, said groove spanning the juncture, and increasing the 55 pressure of the grooved surface of the tool on the blasting cap thereby forming a thermoplastic beading spanning the line of juncture between the bridge plug and the case.
